CORNICLE-WINDING MACHINE

Application filed March 13, 1930, Serial No. 435,395, and in Czechoslovakia June 11, 1927.

The present invention relates to dough coiling machines and particularly to a cornicle winding machine which in contrast with the machines of this character hitherto known entirely dispenses with the use of bands for guiding and shaping the dough. Such bands have a series of considerable disadvantages. The bands easily stretch during the operation of the machine as they absorb moisture, they 10 wear rapidly, and tear, whereby the operation of the machine is disturbed. Suggestions have already been made to effect the winding itself by means of three rollers of which one is yieldingly mounted, but in this connection 15 no consideration was paid to the fact that the pressure of the rollers must be suitably reduced as the winding of the cornicle increases its size.

According to the present invention a variation of the winding pressure, as the size of 20 the cornicle increases, is effected in a simple manner by the use of a yielding winding roller, so that an easily adjustable device is provided which is simple in construction and 25 certain in operation, the winding roller, preferably consisting of soft rubber, being influenced by a cam rigidly connected to a balance lever in such a manner that the roller pressure in the initial position of the winding 30 roller at the commencement of the winding is at its maximum. The yielding winding roller is in this case under the action of a weight, the action being reduced as the size 35 of winding increases, whilst the three rollers are so arranged that they automatically eject the cornicle after it has been completely wound. The movable winding roller then returns to its initial position in which it 40 touches the other two rollers.

A particularly suitable method of arranging the rollers of this machine is shown diagrammatically by way of example in the accompanying drawing, wherein:—

Fig. 1 is a sectional side elevation showing 45 the position of the rollers at the commencement of the winding operation;

Fig. 2 is a front elevation;

Fig. 3 is a detail view showing the position 50 of the rollers at the end of the winding operation.

The machine illustrated in the drawing is provided with five rollers, four of which are grouped around the principal roller 2. In this manner the sheeting roller 5 together with the sheeting roller 1, and the roller 2 55 serve for spreading the dough, and for conveying the rolled sheet of dough to the coiling or winding rollers 3 and 4. The mounting of the rollers 1 and 5, which serve to roll out the dough, is adjustable in the direction 60 of the arrow a preferably in such a manner that the roller 5 only comes into operation for operating upon large pieces of dough. Both these rollers rotate in the opposite direction 65 to the principal roller 2.

The winding of the rolled sheet of dough is effected in a triangular space formed between the rollers 2, 3 and 4 which all rotate in the same direction. The roller 4 is adjustable and is for example mounted in levers b 70 which can freely rock on the shaft of the main roller 2. Against the arm b_1 of one of these rocking levers there presses a cam c , for example in the form of a hook, rotatably mounted at c_1 and connected to a balance 75 weight lever d . Along this lever d there is adjustably mounted a weight d_1 .

The arrangement of the lever d is such that in the highest position of the roller 4, in which it touches both the main roller 2 and 80 the roller 3, the lever arm of the weight d_1 , therefore also the pressure acting on the roller 4, is at its maximum whereas it is reduced as the angle α between the lever arm d and the horizontal plane increases.

The rollers 1, 2, 3 and 5 are preferably made of metal, for example of steel, whilst the roller 4 is preferably made of soft rubber and preferably rotates somewhat faster than the other rollers. In this manner the cornicle is resiliently supported.

The piece of dough e to be operated upon is introduced between the rollers 1 and 2 which roll it into a thin sheet of dough which adheres to the larger roller 2. When it is 95 desired to produce large cornicles the roller 5 is brought into operation in that it is approached towards the roller 2 and locked at a suitable distance therefrom. The roller 5 may be used either to partake in the 100

rolling operation or only to prevent the dough which has been rolled between the rollers 1 and 2 from contracting during its passage to the winding rollers.

5. As soon as the forward edge of the rolled sheet of dough meets the oscillatory roller 4 the dough is raised from the main roller 2 and conducted to the roller 3.

10. As the rollers 2, 3 and 4 rotate in the same direction the piece of dough between them is rolled up whilst the winding space between them is enlarged more and more by the yielding of the oscillatory roller 4 until (see Figure 3) the distance between the rollers 3 and 4 at the completion of the winding has become so large that the completely wound cornicle e_1 falls out automatically. The oscillatory roller 4 then immediately returns to its initial position in which it touches the roller 3. It is obvious that by reason of the peculiar loading by means of the weighted lever d , d_1 the pressure of the oscillatory roller 4 is reduced when a larger quantity of dough is being treated, that is to say the pressure is reduced according to the larger diameter of the completely rolled cornicle.

15. The machine may be driven by a belt pulley mounted on one of the shafts of the rollers, whilst the other rollers are driven by interengaging gears or the like.

I claim:-

1. In a cornicle winding machine the combination of three rollers for the purpose of winding a strip of dough into the form of a cornicle, one of said rollers being so mounted that it exerts upon the dough, which is being wound, a pressure which decreases as the size of the cornicle increases, means operatively connecting said rollers together so as to cause them all to rotate in the same direction, and a weighted lever, in combination with the pressure applying roller, having a loading moment which decreases as the space in which the cornicle is being wound increases, the variation of the loading moment being determined by means of a cam connected to said lever and supporting the pressure applying roller.

2. In a cornicle winding machine the combination with two metal rollers rotating in the same direction of a rubber roller for cooperating with said metal rollers and rotating in the same direction, and means for pressing the rubber roller towards the metal rollers in such a manner that the pressure acting on said rubber roller decreases as the space between it and the said metal rollers increases.

3. In a cornicle winding machine a combination with a pair of metal rollers rotating in the same direction, of levers pivotally mounted on the shaft of one of said rollers, a rubber roller mounted in said levers, and a pivotally mounted counter balanced cam acting on said levers, the arrangement being such that said cam exerts a pressure on said levers which de-

creases as the spacing between the rubber roller and the metal rollers increases.

4. In a dough coiling machine, the combination with a principal roller adapted to support a piece of dough, of a plurality of sheeting rollers cooperating with said principal roller to roll the piece of dough into a sheet, a plurality of coiling rollers cooperating with said principal roller to coil the sheet of dough, one of said coiling rollers being pivotally mounted, and cam means for pressing said pivotally mounted coiling roller against the coil of dough with a pressure which decreases as the size of the coil increases.

5. In a dough coiling machine, the combination with a principal roller adapted to support a piece of dough, of a plurality of sheeting rollers cooperating with said principal roller to roll the piece of dough into a sheet, a plurality of coiling rollers cooperating with said principal roller to coil the sheet of dough, one of said coiling rollers being pivotally mounted, and cam means for pressing said pivotally mounted coiling roller against the coil of dough with a pressure which decreases as the size of the coil increases, one of said sheeting rollers being movable in and out of operative position.

6. In a dough coiling machine, the combination with a principal roller adapted to support a sheet of dough, a plurality of coiling rollers cooperating with said principal roller to coil the sheet of dough, a pivotally mounted frame supporting one of said coiling rollers, and cam means for pressing the pivotally mounted coiling roller against the coil of dough with a pressure which decreases as the size of the coil increases.

7. In a dough coiling machine, the combination with a principal roller adapted to support a sheet of dough, a plurality of coiling rollers cooperating with said principal roller to coil the sheet of dough, a pivotally mounted frame supporting one of said coiling rollers, and cam means for pressing the pivotally mounted coiling roller against the coil of dough with a pressure which decreases as the size of the coil increases, said cam means including a hooked cam engaging the frame and a counterweighted lever pressing said cam against said pivotally mounted frame.

In testimony whereof I affix my signature.
HUGO BLOCH.
